(57) **CLAIM**

The ornamental design for an osteotomy device with an in-vitro alignment component, as shown and described.

DESCRIPTION

FIG. 1 is a front view of an osteotomy device with an in-vitro alignment component, showing my design;

FIG. 2 is a back view of the osteotomy device with an in-vitro alignment component of FIG. 1;

FIG. 3 is a right-side view of the osteotomy device with an in-vitro alignment component of FIG. 1;

FIG. 4 is a left-side view of the osteotomy device with an in-vitro alignment component of FIG. 1;

FIG. 5 is a top view of the osteotomy device with an in-vitro alignment component of FIG. 1;

FIG. 6 is a bottom view of the osteotomy device with an in-vitro alignment component of FIG. 1; and,

FIG. 7 is a front perspective view of the osteotomy device with an in-vitro alignment component of FIG. 1.

The broken lines are directed to environment and form no part of the claimed design.
